(57) **CLAIM**

The ornamental design for a tightening harness, as shown and described.

DESCRIPTION

FIG. 1 is a front perspective view of a tightening harness, showing our new design;

FIG. 2 is a right elevation view thereof;

FIG. 3 is a left elevation view thereof;

FIG. 4 is a top plan view thereof;

FIG. 5 is a bottom plan view thereof;

FIG. 6 is a front elevation view thereof;

FIG. 7 is rear elevation view thereof.

FIG. 8 is a rear perspective view of the tightening harness of FIG. 1, shown in a condition of use; and,

FIG. 9 is a rear perspective view thereof, however the harness is shown tightened in a second configuration for clarity of disclosure.

In the drawings, the broken lines showing a dog depict environmental structure and form no part of the claimed design. In FIGS. 8 and 9, the broken lines showing a leash depict environmental structure and form no part of the claimed design. The equal-length broken lines on the harness straps depict stitching and form no part of the claimed design. All broken lines form no part of the claim.
